FIG. 3.

FIG. 1.

C. Y. Gullion
Inventor:

O. Randolph
Attorneys.

UNITED STATES PATENT OFFICE.

CLIFFORD Y. GULLION, OF HAMILTON, IOWA, ASSIGNOR OF ONE-HALF TO FREDDIE O. DAVIS, OF KNOXVILLE, IOWA.

GUARD.

1,176,890.

Specification of Letters Patent.

Patented Mar. 28, 1916.

Application filed November 25, 1914. Serial No. 874,027.

To all whom it may concern:

Be it known that I, CLIFFORD Y. GULLION, a citizen of the United States, residing at Hamilton, in the county of Marion and 5 State of Iowa, have invented certain new and useful Improvements in Guards; and I do hereby declare the following to be a full, clear, and exact description of the invention, such as will enable others skilled in the art 10 to which it appertains to make and use the same.

This invention comprehends certain new and useful improvements in tongue and neck yoke guards and has for its primary object 15 to provide an improved attachment for tongues, whereby the same may be readily connected with a neck yoke to properly support the forward or free end of the tongue in position.

20 The invention has for another object to provide an improved pole attachment of this character which will prevent the neck yoke ring from slipping from the end of the pole.

The invention has for a still further object to generally improve and simplify the 25 construction and operation of devices of this character and increase the efficiency thereof and provide a connection which will be strong and durable as well as highly efficient in use, and still cheap to manufacture.

With these and other objects in view as will become more apparent as the description proceeds, the invention consists in certain novel features of construction, combination 35 and arrangement of parts as will be hereinafter more fully described and claimed.

For a complete understanding of my invention, reference is to be had to the following description and accompanying drawings, in which—

Figure 1 is a side elevation of a vehicle tongue with my invention applied thereto, Fig. 2 is a detail elevation of the forward 45 end of said tongue with the outer end of my attachment in section, and Fig. 3 is a transverse detail section on the plane of line 3—3 of Fig. 1.

Referring in detail to the drawings by numerals, 1 designates a tongue of the form tapering toward its forward or free end and having its forward circular edge 2 beveled, while the downwardly and forwardly inclined holdback ring 3 is formed around said 55 tongue 1 inwardly of the forward end there-

of. It will be understood that this tongue is of conventional form and may be employed for carriages or wagons or other vehicles, and does not form a part of my invention.

My invention consists, however, of a rearwardly inclined bar 4 upon the forward end of which is formed a ring 5 which extends angularly from said forward end of the bar 4 and is of substantially diamond shape in cross section so as to provide an inner beveled edge 6 for engagement against the beveled forward circular edge 2 of the tongue 1, so that inward movement of the ring 5 upon the tongue 1 is prevented by the small inner central portion 7 of said ring 5. It will be understood that the ring 5 serves also as a protecting means for the forward end of the tongue 1, as the lower portion of said ring 5 will engage the ground or other surface should the forward end of the tongue 1 drop or move downwardly, and thereby prevent the end of the tongue 1 from being damaged.

The inner end of the bar 4 is secured to the tongue 1 rearwardly of the ring 3 which serves to hold back the bar 4 and prevent the same from moving off of the forward or free end of the tongue 1, and in order to secure the bar 4 in proper position upon the tongue 1, I have provided a clamping ring consisting of upwardly curved and oppositely directed arms 9 which project from the opposite sides of the upwardly curved rear end 10 of the bar 4 and have their upper ends enlarged, as shown at 11, and provided with suitable openings extending 80 transversely therethrough to receive the securing screws 12. The securing screws 12 are also passed through the lower flattened and enlarged ends 13 of the semi-circular ring section 14 engaged in said enlarged 85 upper ends 11, it being understood that said enlarged upper ends 11 are bicurcated to receive said enlarged ends 13 of the semicircular ring section 14. It will be seen that by securing the bar 4 to the tongue 1 rearwardly of the ring 3 in this manner, said bar will be securely clamped in position below the tongue 1 and while inward movement of the bar 4 will be prevented by the ring 5, outward movement of the bar 4 will be prevented by the ring 3.

The device may be readily removed from the tongue 1, however, when desired, and should the device become loose upon the tongue 1 by wearing away of the forward end of said tongue 1, 105

it will simply be necessary to place a washer between the rear face of the ring 3 and the arms 9 and semi-circular ring section 14, to draw the device rearwardly upon the tongue 1 and tighten the ring 5 against the forward end of said tongue 1. It will further be evident that this device may be readily and cheaply manufactured and will be highly efficient as well as durable in use, and may 10 be applied to the conventional form of tongues now in general use.

From the foregoing it will be evident that in use the neck yoke is first slipped over the end of the pole in the usual manner and 15 connected thereto in the ordinary way. The ring 5 is then placed in position so that its beveled edge engages the beveled end of the pole and the bar 4 extends rearwardly along the pole and is spaced therefrom, as clearly 20 illustrated. The curved arms 9 of the upward extension 10 it will be apparent will engage the pole in the rear of the ring 3 and the clamping section 14 is then placed so as to straddle the pole to the rear of the ring 25 3 and secured in place by passing the screws or other fastening connections 12 through the apertures provided for that purpose. In this position it will be apparent that the ring of the neck yoke can not slip from its 30 position on the pole or tongue and permit the tongue to drop into engagement with the ground, thus endangering the vehicle or parts thereof.

While I have shown and described the 35 preferred embodiment of my invention, it will be understood that minor changes in the details of construction, combination and arrangement of parts may be made without

departing from the spirit and scope of the invention as claimed or sacrificing any of 40 the advantages thereof.

What is claimed is:-

1. The combination with a tongue having a beveled outer end and a hold back ring, of a bar, a ring formed upon the forward end of said bar and engaged against the beveled end of the tongue, an angular extension on the inner end of the bar, curved arms projecting from the opposite sides of said extension, a semi-circular ring section 50 engaged around the tongue rearwardly of said hold back ring and means for securing the ends of said semi-circular ring section to the free ends of said arms.

2. A device of the class described including a bar, a ring formed on the forward end of said bar for engaging against the end of a tongue, said ring having a beveled face for engagement with said tongue, the rear end of the bar being directed angularly, curved bars projecting oppositely from said angularly extending rear end, the free ends of said arms being bifurcated, a semi-circular clamping section having its opposite ends flattened and engaged in said bifurcated ends of said arms, and means for securing said semi-circular clamping sections and said arms together to clamp the same around the tongue with which the ring is engaged.

In testimony whereof I affix my signature in presence of two witnesses.

CLIFFORD Y. GULLION.
